UNITED STATES PATENT OFFICE.

WILLIAM H. BLATCHLEY, OF PITTSBURGH, PENNSYLVANIA.

COMMUTATOR FOR INTERNAL-COMBUSTION MOTORS.

Application filed March 25, 1922. Serial No. 546,827.

This invention relates to the housing for commutators or timers for internal combustion motors. More particularly it relates to improvements in housings for commutators 5 adapted to be used with the standard Ford automobile motor.

The objects of the invention are to simplify the construction and improve the functioning of the housing for commutators 10 for Ford motors, particularly by rendering such housing oil-tight for the purpose of facilitating lubrication. A further object is to provide a commutator housing which will cooperate with a standard gasket provided on Ford motors surrounding the end of the cam shaft which drives the commutator, and also with a fixed spring provided for holding the commutator housing in place on standard Ford motors. A further 20 object is to provide a housing which will be oil-tight, and which will be sealed by cooperating with standard parts of Ford motor constructions. Other objects and advantages of my arrangement will be apparent 25 to those familiar with the art.

Referring to the drawings, Fig. 1 is a central vertical partial section through my commutator housing as applied to a standard Ford motor construction; Fig. 2 is an 30 elevation of the housing with the cover removed; Fig. 3 is a central section of the housing with the cover removed; and Fig. 4 is a central section of the cover cap removed from the housing.

The standard Ford construction of timers 35 comprises an end of the cam shaft 1 extending through the wall 2 of the engine block and surrounded by an oil sealing resilient washer 3, exactly as illustrated in Fig. 1. Cooperating with these parts the standard 40 construction comprises a plate having a central opening adapted to slide over the cam shaft and to bear against the washer 3, and an open cup shaped shell adapted to bear 45 against the said washer, and to carry a standard contact ring similar to that illustrated in Fig. 2 of the present drawing. It will be understood that in use a roller 50 contact member is mounted on the cam shaft and makes contact with the contacts 5 as illustrated in Fig. 2. Such construction is standard and therefore is not illustrated. A spring arm 15 fixed in the engine structure has its free end adapted to bear against 55 the shell and to press the shell constantly towards the engine block, and so to hold it

in position. One difficulty with such a construction is that oil is not permanently retained therein, seeping out around the edges of the open shell.

In my construction I have obviated this difficulty, and generally improved upon the arrangement and functioning of the parts of the commutator housing, by the arrangement illustrated in the drawings wherein 60 the housing comprises a substantially cylindrical shell portion 7, carrying intermediate its ends an insulating ring 4 having therein the standard metal contact segments 5, following the usual construction of such commutators. The rear wall of the shell 7 is partially closed by a sheet metal back 6, rigidly and tightly attached to the body portion 7 at their meeting edges to form an 65 oil-tight joint. This back wall 6 is indented 70 on its outer side to form a circular recess portion 8, and the central part of this is cut away to form opening 9 adapted to permit passage therethrough of the end of the cam shaft 1, as illustrated in Fig. 1. The portion 8 is adapted to fit over and bear against 75 the outer surface of the standard oil retaining washer 3, as illustrated in Fig. 1. Consequently, when the back wall 6 is pressed 80 against the outer face of the washer 3, the portion 8 being of such a depth that the washer is adapted to form the abutment for 85 the rear wall of the commutator housing; an oil-tight closure of the rear wall of the housing is made by cooperation with the 90 said washer 3.

The body portion of the shell at its other end is threaded at 10, to receive a cover cap 16, which in turn is threaded at 11 so as to fit into and form an oil-tight engagement with the shell member 7, as clearly 95 illustrated in Fig. 1. This cap 16 protrudes outward from the threaded portion in a somewhat conical shape, and has a central 100 terminal oil hole 12 therein, this hole being surrounded by an inturned inwardly flared flange 13. This flared flange prevents oil from escaping through the hole, in obvious manner. The spring arm 15 used with the standard Ford commutator has an indented 105 portion 17 at its free end, and this protuberance is adapted to fit into the opening 12 in the cap 16. Consequently, the pressure of the spring at this point serves the double 110 function of sealing the oil hole in the housing, and pressing the housing as a whole towards the block, and consequently of main-

taining a tight fit between the rear wall 6 thereof and the gasket 3. Consequently with this arrangement the standard washer 6 and the standard spring member 15 co-operate with my form of housing to form oil seals on each side thereof. There are no other openings in the housing through which oil can escape. It will be understood that a rolling contact brush is mounted on 10 the cam shaft inside the contact ring 4, and bears against the inner periphery of that ring as the cam shaft is rotated, making successive contacts with the contact members 5, exactly as in the well understood operation of commutators of this type.

In applying my commutator housing to a Ford motor, the main body member of the housing is slipped over the end of the cam shaft and into contact with the felt washer 20 3. The brush assembly is then slipped over the cam shaft to proper position for making contact in the usual manner, the cap 16 is then screwed into the main body housing, oil is introduced to the housing through the 25 hole 12, and then the spring 15 is positioned as shown at Fig. 1, thus effectively sealing the oil hole, and constantly pressing the entire housing towards the engine block, and consequently making a tight joint between 30 the rear wall 6 and the oil sealing washer 3.

I claim:

1. A commutator casing provided with a body and end walls so associated therewith as to form a lubricant retaining chamber, 35 one of said walls having a lubricant feeding opening therein, and a stationary spring arm provided with a protuberance fitting in said opening whereby to close the opening and to resiliently bind the casing into firm 40 contact with the engine.

2. A commutator casing provided with a body and end walls so associated therewith as to form a lubricant retaining chamber, one of said end walls having a depression 45 therein with a lubricant feeding opening at the bottom of the depression, and a stationary spring arm provided with a protuberance fitting in said opening whereby to close the opening and to resiliently bind the casing into firm 50 contact with the engine.

3. A commutator casing provided with a body and end walls so associated therewith as to form a lubricant retaining chamber,

one of said end walls having a depression therein with a lubricant feeding opening at 55 the bottom of the depression, an annular deflecting baffle surrounding the said opening and projecting within the interior of the housing, and a stationary spring arm provided with a protuberance fitting in said 60 opening whereby to close the opening and to resiliently press the casing into firm contact with the engine.

4. A commutator casing provided with a body and end walls so associated therewith 65 as to form a lubricant retaining chamber, one of said end walls having a depression therein with a lubricant feeding opening at the bottom of the depression, an inwardly 70 projecting annular deflecting baffle surrounding the said opening provided with a concave periphery, and a stationary spring provided with a protuberance fitting in said 75 opening whereby to close the opening and to resiliently force the casing into firm contact with the engine.

5. A commutator casing provided with a cylindrical body and spaced end walls so associated therewith as to form a lubricant retaining chamber, one of said end walls 80 having a depression disposed at the center thereof with a lubricant feeding opening at the bottom of the depression, an inwardly projecting annular deflecting baffle surrounding the said opening provided with a 85 concave periphery, and an anchored spring arm provided with a protuberance fitting in said opening whereby to close the opening and to resiliently press the casing into firm 90 contact with the engine to position the same.

6. A commutator housing for combustion motors comprising a shell having an integral back wall closed except for an opening adapted to fit over the end of the commutator driving shaft, a screw cap adapted to 95 enclose the other side of the shell, said screw cap projecting outward and having a central oil hole therein, a spring normally pressing against the screw cap and sealing the oil hole, and a resilient washer surrounding the 100 driving shaft and positioned between the rear wall of the housing and the engine block and spacing the housing therefrom.

Signed by me at Pittsburgh, Pennsylvania, this 23rd day of March, 1922.

WILLIAM H. BLATCHLEY.
